*A. S. Wedders
Parlor Stove Design
N°. 510*

Patented October 12th 1852

Dec. 510

W. S. Vedder Troy N. Y.

Letters Patent No 510 Dated Oct 12th 1852.

.....

To all whom it may concern:

Be it known that I et. S. Vedder of Troy in the County of Rensselaer and State of New York have invented or produced a new and original design of parlor stove plates, which stove I call the "Fire King" and I do hereby declare that the following is a full and exact description of the same reference being had to the annexed perspective drawing making a part of this specification.

The ornamental design of my stove plates consists in the arrangement of the scalloped moulding (a, a) the rosettes (b, b) and moulding (c, c) disposed on the top plate A

The front plate (B) is of the Gothic style of work and consists in the arrangement of the mouldings (d, d) on the sides, the mouldings (e, e) forming the top window frames (f, f) and bottom one (g) the sides of the plate are ornamented with the rosettes (b, b) and blank niches (h, h) the moulding C at the top of the plate is ornamented with rosettes (b, b) and links (i, i) the vase of the plate is ^{also} ornamented with the rosettes (b, b) and links (i, i) the window (g) is divided into three parts by mouldings (j, j) and has a diamond shaped each (K, K)

Having thus described my design of parlor stove plates. What I claim as new and desire to secure by Letters Patent is the ornamental design and configuration of top and front stove plates such as herein described and represented in the annexed drawings.
